(57) **CLAIM**

The ornamental design for a vehicle filter, as shown and described.

DESCRIPTION

FIG. 1 is an isometric front view of a vehicle filter in accordance with a preferred embodiment of my design;
FIG. 2 is an isometric rear view of the vehicle filter of FIG. 1;
FIG. 3 is a top view of the vehicle filter of FIG. 1;
FIG. 4 is a bottom view of the vehicle filter of FIG. 1; and,
FIG. 5 is a right side view of the vehicle filter of FIG. 1, the left side view being identical thereto.

The dashed lines shown in the figures represent environmental subject matter and form no part of the claimed design.
